UNITED STATES PATENT OFFICE.

ISIDORE HIRTZ, OF NEW YORK, N. Y.

DESIGN FOR A SANDWICH HOLDER.

Application filed October 24, 1925. Serial No. 15,239. Term of patent 7 years.

To all whom it may concern:

Be it known that I, ISIDORE HIRTZ, a citizen of the United States, residing at New York, in the county and State of New York, have invented a new original and ornamental Design for Sandwich Holders, of which the following is a specification, reference being had to the accompanying drawing, forming a part thereof.

The figure is a perspective view of the sandwich holder showing my new design.

I claim:

The ornamental design for a sandwich holder as shown.

ISIDORE HIRTZ.
